Primary Examiner — Jack Reickel(74) *Attorney, Agent, or Firm* — Eversheds Sutherland (US) LLP(57) **CLAIM**

The ornamental design for a display screen with a graphical user interface, as shown and described.

DESCRIPTION

The sole FIGURE is a front view of a display screen with a graphical user interface showing the claimed design.

The broken line showing of the display screen with a graphical user interface is included for the purpose of illustrating portions of the article and forms no part of the claimed design.
